S. WATSON

PULVERIZING ATTACHMENT FOR PLOWS

Filed April 8, 1922

UNITED STATES PATENT OFFICE.

STROTHER WATSON, OF GALLATIN, TENNESSEE.

PULVERIZING ATTACHMENT FOR PLOWS.

Application filed April 8, 1922. Serial No. 550,629.

To all whom it may concern:

Be it known that I, STROTHER WATSON, a citizen of the United States, residing at Gallatin, in the county of Sumner and 5 State of Tennessee, have invented a new and useful Pulverizing Attachment for Plows, of which the following is a specification.

This invention relates to mold boards for plows and more particularly to pulverizing 10 attachments therefor.

The object of the invention is to equip a mold board with pulverizing knives so constructed and set as to render it impossible to choke the plow or prevent its scouring, 15 and which will divide the furrow slice into any requisite number of strips sufficiently small to disintegrate or crumble as they turn over.

Another object is to so construct and 20 mount knives of this character that they will effectively break up and pulverize sod, hard cloddy land, clay and gravel without choking and without causing excessive draft.

Another object is to provide such knives 25 constructed so as to prevent the formation of a dead space at the rear and which are located where pressure is exerted on all plows thereby preventing the mold board wearing through at this point and which 30 will not in any way interfere with the proper operation of the plow share.

With the foregoing and other objects in view which will appear as the description 35 proceeds, the invention resides in the combination and arrangement of parts and in the details of construction hereinafter described and claimed, it being understood that changes in the precise embodiment of the invention herein disclosed may be made 40 within the scope of what is claimed without departing from the spirit of the invention.

In the accompanying drawings:—

Figure 1 represents a side elevation of a 45 mold board and share with this improvement shown applied.

Fig. 2 is a detail longitudinal section thereof.

Fig. 3 is a detail side elevation of one of the cutting blades.

In the embodiment illustrated, a mold 50 board 1 is shown of usual construction provided at its front end with a plurality of longitudinally extending laterally spaced parallel slots 2. A share 3 of ordinary construction is shown provided on its lower face

at its inner end with a plurality of longitudinally extending laterally spaced grooves 4 opening through its inner edge and which are positioned to register with the slots 2 in the mold board when the members are 60 assembled.

Any desired number of these registering slots and grooves may be provided according to the number of pulverizing blades 5 it is desired to use in connection with the 65 plow.

Each of the blades 5 is preferably constructed as shown in detail in Fig. 3 from a thin sheet of steel and each comprises a substantially triangular body portion 6, the 70 edge 7 of which is designed to be arranged on the inner face of the mold board 1 flush therewith while the edge 8 extends toward the front of the board with a point 9 projecting beyond said board. The rear edge 75 10 of the blade 6 is provided with a projection 11, the lower edge 12 of which is spaced from the edge 7 a distance equal to the thickness of the mold board 1 so that when the blade is applied, the projection 12 will 80 rest on the outer face of said board as is shown clearly in Fig. 2. An extension 13 extends rearwardly in alinement from edge 8 and is sharpened on its outer edge 14 to form a cutter which extends from the outer 85 face of the mold board 1 at an angle of about 45°, more or less. The extension 13 may be of any desired length according to the length of the blade it is desired to use and the blade body together with the extension 13 being made of thin sheet steel will 90 occupy a minimum amount of space when applied and prevent the formation of a dead space at the rear of the cutter such as would 95 be likely to prevent scouring of the mold board.

In the use of this device, the blades 5 are removably connected with a plow by inserting them in the slots 2 of the mold board 1 with the projections 11 thereof resting on 100 the outer face of the mold board and with the points 9 projecting beyond the front end of said mold board. The point carrying share 3 is then placed over the blade points 9 with said points extending into the 105 grooves 4 so that these points are completely housed in said grooves and the end walls of the grooves form an abutment for the points of the blades and force them back into clamping engagement with the mold board 110

whereby the blades are securely held in operative position without the use of any fastening elements.

It will thus be seen that the blades 5 may be quickly removed and replaced by simply detaching the share, lifting out the blades, inserting others, and returning the share, or if desired, the share may be returned without replacing the blades.

10 The location of the blades at the lower edge of the mold board avoids excessive draft such as would be occasioned were they attached to the share.

I claim:—

15 1. The combination of a mold board having longitudinally extending slots at its front end, knives to fit in said slots with their front ends projecting beyond the board, and a plow point carrying share having grooves on its lower face opening through its inner edge to fit over said projecting blade ends to hold the blades in operative position.

20 2. The combination with a mold board, and a plow share of a plurality of pulverizing blades, said board, share and blades having cooperating means whereby the blades are held in operative position without the use of fasteners.

25 3. The combination of a mold board having longitudinally extending slots opening through its front end, a plurality of blades removably mounted in said slots, with their cutting edges arranged obliquely relatively 30 to the board, and having pointed front ends projecting beyond the mold board, a share having grooves in its lower face opening through its rear end and positioned to register with the slots in the mold board and define 35 signed to fit over the projecting blade ends to hold the blade in adjusted position.

40 4. The combination of a mold board having longitudinally extending slots opening through its front end, a plurality of blades removably mounted in said slots, said blades being substantially triangular in form with

an extension at one corner arranged in longitudinal alinement with one side edge thereof, the outer edge of said extension and the side edge with which it alines being sharpened to form a continuous cutter, the edge of the blade which extends at right angles to the extension having a projection to fit over the outer face of the mold board to hold the blade in position relative to the board. 50

5. The combination of a mold board having longitudinally extending slots opening through its front end, a plurality of blades removably mounted in said slots, said blades being substantially triangular in form with 60 an extension at one corner arranged in longitudinal alinement with one side edge thereof, the outer edge of said extension and the side edge with which it alines being sharpened to form a continuous cutter, the edge of the blade which extends at right angles to the extension having a projection to fit over the outer face of the mold board to hold the blade in position relative to the board, the 65 edge of the blade body between said projection and the lower body edge being of a length corresponding to the thickness of the mold board.

6. The combination of a mold board having slots in the front end thereof, a pulverizing blade for mounting in one of said slots and comprising a thin sheet steel plate having an obliquely disposed cutting edge, said blade having means for engagement with said mold board whereby said cutting edge 70 is held substantially at an angle of 45° , and a plow share having means for clamping and holding said blade engaged with the mold board.

In testimony that I claim the foregoing as 75 my own, I have hereto affixed my signature in the presence of two witnesses.

STROTHER WATSON.
